(57) **CLAIM**

The ornamental design for a hood for motor vehicle, as shown and described.

DESCRIPTION

FIG. 1 is a perspective view of a hood for motor vehicle showing my new design;

FIG. 2 is a front view thereof;

FIG. 3 is a left side view thereof, the right side view being a mirror image thereof; and,

FIG. 4 is a top view thereof.

The broken lines in the drawings illustrate portions of the hood for motor vehicle that form no part of the claimed design.

1 Claim, 4 Drawing Sheets
